UNITED STATES PATENT OFFICE

UMBERTO MAGNI, OF LOS ANGELES, CALIFORNIA

REVOLVING LAMP

Application filed December 4, 1929. Serial No. 411,561.

This invention relates to revolving lamps for automobiles but primarily has for its object to provide a lamp to be used as an attachment for radiator caps.

5 Another object is to provide means for revolving the lamp by the passage of air going by it.

Another object is to provide a lamp which is of simple construction, inexpensive to 10 manufacture, and of durable construction.

Another object is to provide a lamp of such construction that glasses of different colors may be placed therein and changed at will to any combination of colors desired, the 15 construction being such, that this changing of glasses is easily accomplished.

Still another object is to provide a lamp movable about a vertical axis and having only one thrust bearing to sustain the weight 20 of the lamp which makes for less friction.

Other objects will in part be obvious and in part be pointed out hereinafter.

To the attainment of the aforesaid objects and ends, my invention consists in the novel 25 features of construction and in the combination, connection and arrangement of parts, hereinafter more fully described, and then pointed out in the appended claims.

In the drawings:

30 Figure 1 is a perspective view showing part of an automobile with my invention applied thereto.

Figure 2 is a side elevation of my invention on a radiator cap.

35 Figure 3 is a plan view.

Figure 4 is a horizontal section on the line 4—4 of Figure 2.

Figure 5 is a vertical section on the line 40 5—5 of Figure 4.

Figure 6 is a perspective view of one of the side guide members.

Figure 7 is an enlarged detail sectional view illustrating the manner of holding the 45 lenses in place.

In the drawings in which like numerals of reference indicate like parts in all of the figures, 1 indicates an ordinary radiator cap with a central bore 2 in the top of it, through 50 which extends a post 3 secured to the radiator

cap by upper and lower nuts 4 and 5 respectively.

6 designates the light bulb which is removably held in an ordinary lamp socket 7. Holding the socket 7 securely to the post 3 55 is a bracket 8 which may be soldered or otherwise attached in any suitable manner.

The post 3 is bored at 9 to receive the light wires 10 which enter said bore through an opening 11 and extend down through the bore 9 and out through a lower opening 12 to the source of power (not shown). 60

The lower end of the bore 9 is plugged as at 13, the purpose of which is to keep the steam from the radiator from coming 65 through.

14 represents a flange member, the purpose of which is merely to act as a safety bearing member. 15 represents a collar placed on the post to keep the revolving member from 70 coming off its bearing 16.

The post 3 at its upper end is shaped to a point 16. This point 16 operates in a socket 17 which socket is in a steel block 18. The steel block 18 is securely attached by any suitable means to the top 19 of the lamp. 75

The top 19 is shown as a six sided pyramidal shaped construction, (but it may have any shape desired), having openings 20 and glasses or lenses 21 attached as at 22. The top 19 is bent under at 23 to form a horizontal sealing member. It is also extended down as at 24 to form a flange for the securing of the vertical guides 25. 80

The guides 25 are of U-shape to form a 85 groove 26 for holding the glasses 27. One side of alternate guides 25 is bent back upon itself as at 28 and extends out from the body of the lamp to form air vanes 29.

At the bottom of the guides 25 and extending entirely around is a flange 30, the purpose of which is to form a securing means for the lower ends of the guides 25. These guides 25 where they are attached to the top flange 24 or the flange 30, may be secured in any suitable manner as by welding or soldering. At the bottom of the guides, for the purpose of retaining the glasses 27, one of the corners of the guides 25 is bent under as at 31 as is clearly shown in Figure 7 of the drawings. 90 95 100

The flange 30 is an extension of the bottom member 32. The bottom has drain holes or vents 33 for the purpose of allowing any water which may seep in, to drain off. The bottom 32 has a center opening 34 which encircles the post 3 and acts as a guide in the lamp's revolving around the post 3.

While I have shown my lamp as mounted on a radiator cap it may be mounted on any suitable bracket at any desired location on the vehicle.

From the foregoing description, taken in connection with the accompanying drawings, it is thought the complete construction, operation and advantages of my invention will be clear to those skilled in the art to which it relates.

What I claim is:

1. In combination with a radiator cap, a supporting column directly connected to said cap and supported thereby, and having its upper end tapered to form a thrust bearing, a revoluble open frame lamp body rotatably supported on said bearing, said open frame comprising upper and lower flanged members, vertical uprights supported on said flanged members, removable glasses slidable in said uprights and means to hold said glasses in place against sliding in the uprights.
2. In combination with a radiator cap, a supporting column directly connected to said cap and supported thereby, a revoluble open frame lamp body rotatably supported on said column, said body comprising upper and lower flanged members, vertical U-shaped uprights attached to said upper and lower members, one side of alternate U-shaped uprights being bent to form air vanes.
3. In combination with a radiator cap, a supporting column directly connected to said cap and supported thereby, a revoluble open frame lamp body rotatably supported on said column, said body comprising upper and lower flanged members, vertical U-shaped uprights attached to said upper and lower members, a plurality of glasses slidable in said U-shaped uprights, said uprights at their lower extremities being crimped to form abutments to retain said glasses.

UMBERTO MAGNI.
